UNITED STATES PATENT OFFICE.

RICHARD WOLFFENSTEIN, OF BERLIN, GERMANY.

PROCESS FOR THE PRESERVATION OF FEATHERS.

No. 800,197.

Specification of Letters Patent.

Patented Sept. 26, 1905.

Application filed June 1, 1903. Serial No. 159,717.

To all whom it may concern:

Be it known that I, RICHARD WOLFFENSTEIN, a subject of the German Emperor, residing in Berlin, Prussia, Germany, (whose 5 post-office address is 14 Landgrafenstrasse, Berlin, Germany,) have invented a certain new and useful Process for the Preservation of Feathers, (for which I have applied for a patent in Germany on the 7th of March, 1903,) 10 of which the following is a specification.

Ostrich and other ornamental birds' feathers have the defect that they deteriorate in the course of time, inasmuch as feathers which originally were erect and beautifully 15 curled gradually collapse during use or wear, lose their curl, and become unsightly and dull. This collapse of the feather is caused by the fact that the fine twigs or filaments of the individual feathers gradually absorb moisture 20 from the atmosphere, thereby increasing in weight, and lay themselves against the natural point of support—that is to say, the quill of the feather—in consequence of which the feather assumes a thinner and somewhat 25 crumpled appearance.

The present invention has for its object to avoid the frequent necessity for redressing, restoring, or renovating the feathers, whereby their life is shortened and the wearing of 30 such feathers is rendered expensive—in other words, to maintain the feathers in their curled condition. For this purpose the feathers are treated with a water-repellent substance—that is to say, a substance which will not take up 35 moisture, such as wax—in a suitable solution.

I prefer to use as a vehicle for the water-repellent substance a volatile solvent which will not injure the feather and subsequently to remove the solvent by gentle heating, so as 40 to leave on the feather a thin coating of the

water-repellent substance, which is preferably a colorless organic substance soluble in alcohol. For this purpose the ostrich or other feathers to be preserved are dipped into a one-per-cent. solution of wax in methyl alcohol either before or after the curling of the feathers, and the methyl alcohol used as a solvent is subsequently evaporated. The further treatment of the feathers is the same as usual.

It is not new to render the surface of woven fabrics waterproof or water-repellent by coating them with a solution of shellac, paraffin, or india-rubber; but for the treatment of ostrich-feathers such waterproofing compositions are 45 not suitable, because they cause the fine filaments or twigs to stick together and destroy the fine voluminous appearance and the brilliancy of the feathers. They fail to maintain the curly appearance of the feathers, which 50 is the principal object of my new invention.

What I claim is—

1. The process for preserving ornamental birds' feathers, which consists in dipping them into an alcoholic solution of wax and then 55 driving off the solvent, substantially as described and for the purpose specified.

2. The process for preserving ornamental birds' feathers, which consists in applying to them a dilute solution of wax in methyl alcohol and then driving off the solvent, substantially as described and for the purpose specified.

In witness whereof I have hereunto signed my name in the presence of two subscribing 75 witnesses.

RICHARD WOLFFENSTEIN.

Witnesses:

LUDWIG WENGHÖFFER,

HANS BREMNER.
